UNITED STATES PATENT OFFICE

133,188

DESIGN FOR A SURFACE GRINDER

James W. Wilkie, Minneapolis, Minn., assignor to
Savage Tool Company, Minneapolis, Minn., a
corporation of Delaware

Application May 1, 1942, Serial No. 106,766

Term of patent 14 years

To all whom it may concern:

Be it known that I, James W. Wilkie, a citizen of the United States, residing at Minneapolis, in the county of Hennepin and State of Minnesota, have invented a new, original, and ornamental Design for a Surface Grinder, of which the following is a specification, reference being had to the accompanying drawings, forming part thereof.

Figure 1 is a perspective view showing the front, top and one side of a surface grinder embodying my new design;

Figure 2 is a perspective view showing the front, top and opposite side of the surface grinder; and

Figure 3 is a perspective view of the rear of the surface grinder.

The dominant features of the design reside in the portions shown in full lines.

I claim:

The ornamental design for a surface grinder, as shown and described.

JAMES W. WILKIE.
